US00D816635S

(12) **United States Design Patent** (10) **Patent No.:** **US D816,635 S**
Miller et al. (45) **Date of Patent:** **** May 1, 2018**

(54) **AUDIO DEVICE**

(71) Applicant: **Bose Corporation**, Framingham, MA (US)

(72) Inventors: **Joel H. Miller**, Westborough, MA (US); **Alexander Decastro Calachan**, Belmont, MA (US); **Mitchell Joseph Silva**, Groton, MA (US)

(73) Assignee: **Bose Corporation**, Framingham, MA (US)

(**) Term: **15 Years**

(21) Appl. No.: **29/570,371**

(22) Filed: **Jul. 7, 2016**

Related U.S. Application Data

(63) Continuation-in-part of application No. 29/558,566, filed on Mar. 18, 2016.

(51) **LOC (11) Cl.** **14-01**

(52) **U.S. Cl.**

USPC **D14/205**

(57) **CLAIM**

The ornamental design for audio device, substantially as shown and described.

DESCRIPTION

FIG. 1 is a perspective view of an audio device as seen from the front, top and left side;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The ornamental design is shown on an audio device in FIGS. 1 through 7.

The dotted line portions of the drawings represent environmental structure only and do not form part of the claimed design.

1 Claim, 6 Drawing Sheets
